CLAIM

The ornamental design for a combination urn and picture frame, as shown and described.

DESCRIPTION

FIG. 1 is an elevated front view of the ornamental design for a combination urn and picture frame showing my new design;

FIG. 2 is a side view, the other side being a mirror image thereof;

FIG. 3 is a rear view thereof;

FIG. 4 is a bottom view thereof;

FIG. 5 is a top view thereof; and,

FIG. 6 is a side view of a section of the picture frame portion of the present invention, the other side being a mirror image thereof.
